(57) **CLAIM**

The ornamental design for a kickball home plate, as shown and described.

DESCRIPTION

FIG. 1 is a perspective view of the kickball home plate showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is another top plan view showing the addition of indicia in broken lines; and,

FIG. 9 is a plan view showing an alternative bottom surface configuration in broken lines.

The broken lines in FIG. 5 are included for the purpose of illustrating the portions of the bottom surface that form no part of the claimed design. The broken lines showing the indicia in FIG. 8 and the alternative bottom surface in FIG. 9 are for illustrative purposes only and form no part of the claimed design.
